UNITED STATES PATENT OFFICE.

FREDRICK FRAZER, OF SYRACUSE, NEW YORK.

DESIGN FOR A TRACE-CARRIER.

SPECIFICATION forming part of Design No. 18,724, dated November 6, 1888.

Application filed October 13, 1888. Serial No. 288,005. Term of patent 3½ years.

To all whom it may concern:

Be it known that I, FREDRICK FRAZER, a citizen of the United States, residing at Syracuse, in the county of Onondaga and State of New York, have invented and produced a new and original Design for Trace-Carriers; and I do hereby declare the following to be a full, clear, and exact description of the same, reference being had to the accompanying drawings, forming a part thereof.

Figure 1 is a plan view of a trace-carrier showing my new design. Fig. 2 is a side view of the same.

The new design, in plan view as shown in Fig. 1, appears somewhat in the form of an oval-shaped frame, being provided with the curved side bars, *a*, and the curved end bars, *b*, the said bars *a* and *b* forming the base of the carrier and being on the same plane. From these outer bars rise the other parts of the carrier, gradually increasing in elevation inwardly from the end bars, *b*, the highest portions being at the central part of the article. The curved cross-bars *c* are supported in position higher than the end bars, *b*, and the bars *d*, curving upward and inward, rise higher than the bars *c* and are nearer the middle of the carrier. A

series of curved limbs, *e*, extend from the opposite bars *d* over the space between said bars, but do not extend entirely from one bar to the other, as seen in Fig. 1. Three limbs, *e*, are shown, two of which extend from one of the bars *d* over toward the opposite bar *d*, from which one curved limb extends over between the two other limbs, as shown in the drawings. 30 35

The trace-carrier thus formed bulges upward from the outer bars, and in side view presents somewhat the appearance of an arch, as seen in Fig. 2.

I claim—

The design for a trace-carrier herein shown and described, comprising a base formed of curved end and side bars, a number of curved cross-bars, which rise to different elevations from the base, and a series of curved limbs, *e*, 45 extending from the two opposite bars *d* over the space between said bars, as shown and described.

In testimony whereof I affix my signature in presence of two witnesses.

FREDRICK FRAZER.
